METHOD OF PURIFYING SUGAR

Louis Hyve, Marseille, France

Application August 4, 1932, Serial No. 627,510
In France August 19, 1931

3 Claims. (Cl. 127—64)

My invention relates to improvements in means of purifying sugar.

It has already been proposed to refine or purify sugar by submitting masses of sugar to be refined to the action of sugar solutions of increasing purity while being displaced in a direction opposite to the one of said sugar solutions, in order to remove from the crystals of sugar the nearly solidified mother lies which surround every crystal.

10 Certain devices of such kind are however connected with the drawback that they do not allow the sugar to be purified to be conveniently treated by the treating solution, so that at the end of the treatment some impurities are still present with the crystals of sugar which it is thus nearly practically impossible to obtain in a convenient pure state.

20 By the purifying means according to my invention, the sugar brought into the form of a paste is laid under a thin layer upon a conveniently moving sieve receiving the action of a purifying sugar solution which is projected upon said layer with a convenient living force with a view to secure a progressive displacement of the impure syrup which surrounds the crystals to be purified and which thus progressively leaves said crystals and makes it escape through the apertures of the sieve while the purifying syrup remains above said surface, the very small passages existing between the crystals and the viscosity of the solution preventing both syrups to become mixed at the surface of their contact.

30 The living force of the purifying syrup is obtained by projecting under the shape of a shower-bath the purifying syrup, this result being obtained either by means of jet under pressure or of a rain of drops falling down from a convenient given height, while the sieve which occupies a horizontal or conveniently inclined position, is given a convenient movement.

40 The shower devices are preferably stationary and washing devices are provided at the end of the displacement of the sugar to be purified, the pure syrup having completely displaced the impure pasting syrup which will drop into a convenient tub under the device.

45 According to a modification it would be possible to use instead of a single pure syrup, several syrups with increasing purities, the dropping of washed syrups taking place in convenient corresponding separated tubs.

50 The removing of impure syrup under the sieve will be favoured by means of scraping devices or suction devices and at the end of the travel, pulverized water or steam will be projected upon the

substance to be purified, a convenient temperature, about 40° C., will favor the operation.

Above means are of a completely mechanical kind and do not require any manual labor. The operation is very quick so that no inversion of syrups can take place during the process.

In the accompanying drawings which show by way of example a diagrammatical showing of a preferred embodiment of a device for purifying sugar according to my invention:—

Fig. 1 is a diagrammatical front view of said device.

Fig. 2 is a partial plan view of the device according to Fig. 1, the tank containing the purifying syrup, having been removed.

Fig. 3 is a part side view of Fig. 1 showing the arrangement of the carrying parts which support the sugar to be purified.

The sugar to be purified conveniently mixed with impure syrup so as to constitute a kind of paste, is contained in a tank 2, and a transporting device 1 takes the paste from tank 2 to a hopper 3 provided with a convenient mixing device, and connected with a chute 4 the lower end of which is arranged at the vicinity of a carrying sieve constituted by foraminated metal plates 22, the dimension of the perforations of said plates being sufficiently small in order to prevent the falling of the crystals to be purified.

Said plates are conveniently connected with one another preferably by means of convenient hinges with as small clearances as possible thus constituting an endless sieving surface. Said surface is conveniently carried by means of extreme drums 6, 7, one of which, for instance 7, is connected with a convenient motor not shown in the drawings and causes the device to be displaced in the direction of arrows F in Fig. 1.

The foraminated metal plates are provided with vertical flanges 23 and are conveniently guided by means of rollers 24 (Fig. 3) conveniently arranged so as to secure a rectilinear either horizontal or conveniently inclined shape to the carrying surface thus constituted.

Located above the upper part of the endless carrying surface thus constituted, is a tank 25 containing the purifying syrup, the degree of purity of which is conveniently regulated. Said tank 25 is provided in its bottom with series of apertures 26 of convenient cross section.

A tub 27 located under the sieve constituted by foraminated metal plates 22 and also under the tank 25, is provided with a bottom 28 conveniently inclined and provided at its lower end with a suction chamber 29 for a pump not shown

in the drawings and the delivery pipe 38 of which is connected with the distributing tank 3.

Convenient washing nozzles 31 are located in the vicinity of the drum 1 quite near the place where the sieves end their working stroke. A receiving plate 32 located below the sieves ends into a collecting tank 33. A pump 34 connected with said tank 33 through its suction pipe delivers liquid into tank 25 through a pipe 35.

10 The operation is as follows:—

The sugar being pasted in tank 2, is carried by means of noria 1 to the distributing hopper 3 which delivers it through its chute 4 with a small and regular thickness upon the transporting surface 22 in proportion of the displacement of foraminated metal plates 22 under the operation of drum 1.

Each of said foraminated plates 22 having thus received a convenient quantity of pasted sugar under a small regular thickness, travels under tank 25 and receives during said travelling a rain of purifying syrup. Said syrup, owing to its living force, progressively displaces the pasting impure syrup which surrounds or encloses the crystals exposed on the foraminated plates 22, said displacement being effected thanks to the shower produced by said purifying syrup thanks to the head of water.

Said impure syrup is thus progressively repulsed or forced and compelled to cross the perforations of metal plates 22, while the purifying syrup remains between the crystals for the viscosity and the very small intervals existing between the crystals do not allow in a noticeable manner the mixing of the syrups at the surface of contact of said both syrups.

The impure pasting syrup falls down into the tub 27, said falling down being preferably rendered easier or quicker by means of scraping devices or suction devices located under foraminated metal plates 22 and not shown in the drawings. Said waste pasting syrup is sent back from tub 27 through pipe 38 into the hopper 3 from which the part of said syrup which is most charged in impurities flows away through a canal 36 provided with a sieve into the mixing or pasting tank 2. Said tank itself delivers as usual the most impure part of its contents to the usual wastes such as molasses or by-products.

50 When arriving at the motive drum 1 the foraminated metal plates 22 are brought under the nozzles 31 which project upon the washed sugar crystals jets of warm water thus causing said sugar to melt and to constitute a syrup which is collected in the tank 33, which tank receives also the drops falling down upon the plate 32 during the travelling of foraminated plates 22 from drum 1 to drum 6. During the return of said plates, they may be rinsed by 55 means of water which is besides directly used for melting the washed sugar.

A part of the syrup thus collected in the tank 33, after having been reduced for instance by evaporation in order to prevent same from dissolving crystals, is sent back into tank 25 as a purifying syrup.

It will sometimes be better, for instance for treating some raw sugars, to substitute foraminated plates 22 for an endless wire gauze comprising

or not swiveling meshes. It would also be possible to use an endless belt conveniently foraminated and made of any convenient substance.

It would be, in some instances, advisable to use the plant shown in Figs. 4 to 6 comprising also the tank 2, the noria 1, the distributing hopper 3 and the chute 4, in which sugar is received in a series of baskets 5 comprising each, as shown in Fig. 6, a box 16 the bottom of which is constituted by a wire gauze 17, the several baskets being connected with each other by means of hooks 18 thus constituting an endless chain carried and moved by drums 6, 7.

The endless chain travels above a row of tubs 15 8, 9, 10, carrying at their lower end pumps 11, 12, 13, which receive the syrup gathered in tanks 10, 9, 8, and deliver same above the chain of baskets as shown in Fig. 1, the pump 13 of the last tank 8 delivering its syrup to the hopper 3 through a canal 14, scrapers such as 15, Figs. 4 and 6, being arranged under the lower face of said baskets, for causing the pasting syrup to more easily fall down into the receiving tubs.

Said baskets may be carried on uneven rails 20. 25 What I claim is:

1. An apparatus for purifying sugar comprising a traveling sieve for receiving the pasted sugar to be purified in a very thin bed, means for projecting a purifying syrup upon said sugar to be purified in the form of a large number of minute droplets with such force as not to displace the crystals of the pasted sugar and merely to displace gradually the impure syrup upon said crystals towards the bottom of said bed of pasted sugar until said impure syrup has been displaced by said purifying syrup, means for collecting the impure syrup so displaced and means for collecting the sugar so refined and purified.

2. An apparatus for purifying sugar comprising a traveling sieve for receiving the pasted sugar to be purified in a very thin bed, a tank located above said sieve containing a purifying syrup, said tank having minute perforations in the bottom thereof for allowing said purifying solution to fall down upon said sugar to be purified in the form of a large number of minute droplets with such force as not to displace the crystals of the pasted sugar and merely to displace gradually the impure syrup upon said crystals towards the bottom of said bed of pasted sugar until said impure syrup has been displaced by said purifying syrup, means for collecting the impure syrup so displaced by said minute droplets and means for collecting the sugar so refined and purified.

3. The method of purifying sugar comprising spreading the pasted sugar in a thin bed, then projecting a purifying syrup upon said bed of pasted sugar in the form of a large number of minute droplets with such force as not to displace the crystals of the pasted sugar and merely to displace gradually the impure syrup upon said crystals towards the bottom of said bed of pasted sugar until said impure syrup has been displaced by said purifying syrup, then collecting the impure syrup so displaced and then collecting the sugar so refined and purified.

LOUIS HYVE.
